COMBINED MEASURING AND DISPENSING CLOSURE

Robert J. Donoghue, 4 Burnwood Drive,
Bloomfield, Conn. 06002

Filed Aug. 26, 1974, Ser. No. 500,646

Term of patent 14 years

Int. Cl. D9—07

U.S. Cl. D9—277

FIG. 1

FIG. 2

FIG. 1 is a top plan view of a combined measuring and dispensing closure embodying my new design; and

FIG. 2 is a front elevational view of the combined measuring and dispensing closure, the opposite side being a mirror image thereof.

I claim:

The ornamental design for a combined measuring and dispensing closure, substantially as shown and described.
